UNITED STATES PATENT OFFICE.

CHARLES H. FOSTER, OF ST. LOUIS, MISSOURI.

BOILER-STAND.

No. 828,882.

Specification of Letters Patent

Patented Aug. 21, 1906.

Application filed April 23, 1905. Serial No. 257,852.

To all whom it may concern:

Be it known that I, CHARLES H. FOSTER, a citizen of the United States, residing at the city of St. Louis, State of Missouri, have invented a certain new and useful Boiler-Stand, of which the following is such a full, clear, and exact description as will enable any one skilled in the art to which it appertains to make and use the same; reference being had to the accompanying drawings, forming part of this specification.

In a prior application, Serial No. 231,324, filed by me November 4, 1904, I have shown and described a boiler-stand adapted to engage with the curved lower end of a range-boiler within the flange thereof.

The present application relates to a boiler-stand somewhat similar to the one above referred to, but which is arranged to engage with the lower edge of the flange itself in place of with the bottom of the boiler within the flange, and consequently can be used on range-boilers of any kind without regard to the shape of the bottom.

In the accompanying drawings, which illustrate a stand made in accordance with my invention, Figure 1 is a side elevation of the stand, together with a portion of the boiler carried thereby. Fig. 2 is a top plan view of the stand as shown in Fig. 1; and Figs. 3 and 4 are enlarged end and side views, respectively, of the upper end of one of the supporting members.

Like marks of reference refer to similar parts in the several views of the drawings.

The stand is composed of supporting members 10, preferably three in number. Each of the supporting members 10 is provided at its lower end with a foot 11 and at its upper end with an extension 12, carrying the bearing for engaging with the boiler, as will be hereinafter described. In the form of stand shown in Figs. 1 and 2 each of the supporting members 10 is provided with a curved wing 14, the three wings 14 being so shaped as to form a plain ring when the parts are secured in position. Two of these wings 14 are provided with hooks 15, adapted to interlock with the flanges of adjacent members, and the third is provided with a lug 16, which is secured, by means of a bolt 17, to the flange of the adjacent member 10. As this construction is described and claimed in my prior application above referred to, it will not be more fully described in the present instance.

The upper end 12 of each of the supporting

members 10 is provided with a lug 18, extending radially inward. Each of the lugs 18 is provided with a slot 19.

20 represents bearing-pieces, one of which is pivoted to each of the lugs 18 by means of a bolt 21 passing through an opening in the said bearing and through the slot 19 of said lug and provided with a nut 22. The outer end of each of the bearing-pieces 20 is provided with a finger 23 for engaging with the periphery of the boiler 24, while the upper edge of the said bearing-piece 20 is adapted to engage with the lower edge of the flange of said boiler. The slot 19 allows the bearing-piece 20 to be adjusted readily, so as to adapt the stand to boilers of different diameters.

25 is a stop carried by each of the lugs 18 and projecting over the upper edge of the bearing-piece 20. Some distance is left between the lower edge of the stop 25 and the upper edge of the bearing 20, as is shown in dotted lines in Figs. 3 and 4, the object of this being to allow a certain amount of vertical movement to the bearing-piece 20, so that the boiler can be brought into plumb. This is accomplished by inserting a wedge between the lower edge of the bearing-piece 20 and the upper end of the member 12. This wedge may be a thin strip of metal 26, as shown in Fig. 3. The upper end of the member 12 is preferably provided with a guide 27 for guiding the vertical movement of the bearing-piece 20. It will be readily apparent that by loosening the nuts 22 the bolts 21 can move in the slots 19, so as to allow the radial adjustment of the bearing-pieces 20, in order that their fingers 23 may be brought against the peripheries of boilers of different sizes and that the boiler can be readily trued or plumbed by inserting wedges 26 under one or more of the bearing-pieces 20, as may be required.

Having fully described my invention, what I claim as new, and desire to secure by Letters Patent of the United States, is—

1. In a boiler-stand, the combination with a plurality of connected supports forming a base, of a radially and vertically adjustable bearing for the boiler carried by the upper end of each of said supports.
2. In a boiler-stand, the combination with a plurality of connected supports forming a base, of a radially and vertically adjustable bearing for the boiler carried by the upper end of each of said supports, and means for fastening said bearings in position.

3. In a boiler-stand, the combination with a plurality of connected supports forming a base, of a radially-sliding member carried on the upper end of each of said supports and vertically adjustable, and means for limiting the vertical movement of said sliding member.

4. In a boiler-stand, the combination with a supporting-base, of a radially-sliding member carried on the upper end of said base, and vertically-adjustable means for limiting the

vertical movement of said sliding member, and means for fastening said member in position.

In testimony whereof I have hereunto set my hand and affixed my seal in the presence of the two subscribing witnesses:

CHARLES H. FOSTER. [L. s.]

Witnesses:

W. A. ALEXANDEE.
BENNETTE PIKE.
